US00D954029S

(12) **United States Design Patent** (10) **Patent No.:** **US D954,029 S**
(45) **Date of Patent:** **** Jun. 7, 2022**

(54) **WIRELESS EARPHONE**

(71) Applicant: **SHENZHEN HUOER TECHNOLOGY CO., LTD**, Shenzhen (CN)

(72) Inventor: **Shuiping Guo**, Ji 'an (CN)

(73) Assignee: **SHENZHEN HUOER TECHNOLOGY CO., LTD**, Shenzhen (CN)

(**) Term: **15 Years**

(21) Appl. No.: **29/800,177**

(22) Filed: **Jul. 19, 2021**

(51) LOC (13) Cl. **14-01**

(52) U.S. Cl.

USPC **D14/223**

(58) **Field of Classification Search**

USPC D14/223, 205; D24/174; 128/864-866; 381/380-381

Primary Examiner — Paula Allen Greene

(57) **CLAIM**

The ornamental design for a wireless earphone, as shown and described.

DESCRIPTION

FIG. 1 is a first perspective view of a wireless earphone showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the wireless earphone in which the design is embodied that form no part of the claimed design.

1 Claim, 8 Drawing Sheets
